(57) **CLAIM**

The ornamental design for a tool box, as shown and described.

DESCRIPTION

Embodiment 1

FIG. 1 is a right front perspective view of our new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

Embodiment 2

FIG. 8 is a right front perspective view.

FIG. 9 is a front view thereof.

FIG. 10 is a rear view thereof.

FIG. 11 is a left side view thereof.

FIG. 12 is a right side view thereof.

FIG. 13 is a top view thereof; and,

FIG. 14 is a bottom view thereof.

The broken lines shown in the drawings illustrate portions of the underside of the handle and elements of the tool box to which the handle is latched and form no part of the claimed design.
